UNITED STATES PATENT OFFICE.

JAMES H. TOZER AND WILLIAM TOZER, OF LONDON, ENGLAND.

SECURING RAILWAY-CHAIRS AND RAIL-CLIPS TO METALLIC SLEEPERS.

SPECIFICATION forming part of Letters Patent No. 356,016, dated January 11, 1887.

Application filed November 17, 1886. Serial No. 219,130. (No model.)

To all whom it may concern:

Be it known that we, JAMES HONIBALL TOZER and WILLIAM TOZER, of London, England, engineers, have invented certain new and useful Improvements in Securing Railway-Chairs and Rail-Clips to Metallic Sleepers, of which the following is a specification.

The primary object of our invention is to provide more efficient means of securing railway-chairs to metallic sleepers. With this object we make the chair with one or more holes flanged on the under side, and we make the sleeper with corresponding but unflanged holes, which the flanges on the chair will fit. We pass the flanges of the chair into or through the corresponding holes in the sleeper, and then secure the parts together by riveting. This riveting may be effected in several ways. According to the preferred way, we make the flanges of the flanged holes in the chair long enough to project some distance beyond the holes in the sleeper, we rivet or press over the projecting part against the under side of the sleeper, and we finally insert rivets through the flanged holes and rivet these rivets over upon the riveted or pressed-over flanges, the rivet-heads bearing upon the top of the chair. According to another way, the flanges of the flanged holes in the chair are not made long enough to project beyond the holes in the sleeper, and in this case, after inserting the flanges, we pass rivets through the flanged holes and rivet these rivets against the under side of the sleeper, their heads bearing upon the chair, as in the first way. According to another way, we dispense with separate rivets and secure the parts together by merely riveting or pressing over the projecting part of the flanges against the under side of the sleeper, as in the first way.

The flanged holes may be formed in the chair by means of presses or otherwise. The holes will generally be made in flat portions of the chair, and the configuration of the chair and its jaws will depend upon the section of the rail to be secured therein, whether flat-bottomed, bull-headed, or other sections.

It is obvious that the position of the flanges may be reversed—that is to say, the holes in the sleeper may be flanged at their upper side

and the chair have corresponding unflanged holes to receive the flanges on the sleeper.

Our invention comprises the application of the same means to securing rail-clips to sleepers—that is to say, that when, instead of an entire chair being used, the rail has its seat directly upon the sleeper itself, or upon a pad or layer of felt or other material laid thereon, and the sleeper has clips taking the place of chair-jaws to hold the rail in position, we secure said clips to the sleepers precisely in the manner above described in respect of chairs.

In the accompanying drawings, Figures 1 and 2 are vertical sections illustrating the preferred way of carrying out our invention as applied to chairs suitable to receive bull-headed and flat-bottomed rails, respectively. *a* is the sleeper, made with plain or unflanged holes at *b b*. *c* is the chair, formed with corresponding holes at *d d*, these holes being formed with flanges *e e*, which fit the holes *b b*. After passing the flanges *e e* into the holes *b b*, the portions of the flanges that project beyond these holes are riveted or pressed over against the under side of the sleeper, as seen at *f f*. *g g* are rivets, which are then passed through the flanged holes and riveted over against the riveted or pressed-over parts *f f* of the flanges *e e*, their heads bearing upon the top of the chair, as shown.

Fig. 3 illustrates the modification in which the flanges *e e* are not long enough to project beyond the corresponding holes *b b*. In this case, after passing the flanges *e e* into the holes *b b*, the rivets *g g* are inserted and riveted over against the under side of the sleeper.

Fig. 4 illustrates the modification in which no separate rivets are employed. In this case the chair is secured to the sleeper by merely riveting or pressing over the projecting part of the flanges *e e* against the under side of the sleeper, as seen at *f f*.

Fig. 5 illustrates a modification in which the flange is reversed—that is to say, in which the sleeper has flanged holes to enter plain or unflanged holes in the chair. No separate rivets are shown in this figure; but of course they can be used, if desired.

For convenience of manufacturing the chairs, particularly those having jaws (such as seen

in Fig. 1) to receive bull-headed or double-headed rails, they may be formed in two pieces, each piece carrying one jaw. The pieces, when in place on the sleeper, would 5 meet, preferably, below the seat for the rail, as indicated by the dotted line *h* in Fig. 1.

Fig. 6 illustrates the application of our invention to securing rail-clips to sleepers. *c* is the rail-clip, formed with a hole, *d*, with flange 10 *e*, which is passed through the corresponding hole *b* in the sleeper *a*, and then riveted over, as at *f*, after which a rivet, *g*, is passed through the hole *d* and riveted over the part *f*. *c'* is the clip for the other side of the rail. It may 15 be secured either by a bolt and nut, as shown, or by the same means as the clip *c*, in which latter case one side of the rail would be fixed by a key driven in between it and one of the clips.

2c What we claim, and desire to secure by Letters Patent, is—

1. As means of securing railway-chairs or rail-clips to metallic sleepers, one or more flanged holes in the chair or clip and corresponding unflanged holes in the sleeper, (or vice versa.) the flanges of said flanged holes being inserted into said unflanged holes and the parts being then secured by riveting, substantially as set forth. 25

2. As means of securing railway-chairs or rail-clips to sleepers, a flanged hole, *d*, in the chair or clip and a corresponding unflanged hole, *b*, in the sleeper, the flange of said flanged hole *d* being passed into and through said hole *b*, and its projecting end being then riveted or pressed over against the under side of the sleeper, substantially as and for the purpose set forth. 35

3. As means of securing railway-chairs or rail-clips to sleepers, a flanged hole, *d*, in the 40 chair or clip, a corresponding unflanged hole, *b*, in the sleeper, the flange of said flanged hole being passed into and through said hole *b*, and its projecting end being then riveted or pressed over against the under side of the 45 sleeper, and a rivet, *g*, passed through said flanged hole *d* and then riveted over upon the riveted or pressed-over part of the flange, the rivet-head bearing upon the top of the chair, substantially as and for the purpose set forth. 50

In witness whereof we have hereunto signed our names in the presence of two subscribing witnesses.

JAMES H. TOZER.
WILLIAM TOZER.
